WILLIAM C. TREGONING, OF CLEVELAND, OHIO, ASSIGNOR TO THE TREGONING ELECTRIC MANUFACTURING COMPANY, OF CLEVELAND, OHIO, A CORPORATION.

SOCKET AND TERMINAL CONNECTION FOR ELECTRIC LAMPS.

1,075,613.

Specification of Letters Patent. Patented Oct. 14, 1913.

Application filed June 5, 1911. Serial No. 631,313.

To all whom it may concern:

Be it known that I, WILLIAM C. TREGONING, a citizen of the United States, residing at Cleveland, in the county of Cuyahoga and State of Ohio, have invented certain new and useful Improvements in Sockets and Terminal Connections for Electric Lamps, of which the following is a specification.

My invention relates to improvements in 10 sockets and terminal connections for electric lamps, and my general object is to simplify the construction of the socket in several material features to obtain various improved results, substantially as herein shown 15 and described and more particularly pointed out in the claims.

In the accompanying drawings, Figure 1 is a sectional elevation of a socket embodying a portion of my improvement, and Fig. 2 is a cross section corresponding to line 2—2, Fig. 1. Fig. 3 is a perspective view of the socket member alone, and Fig. 4 is a sectional elevation corresponding to Fig. 1, but at right angles thereto, disclosing the electric terminals. Fig. 5 is a cross sectional view corresponding to line 2—2, Fig. 1, with the attachments seen in Fig. 2 removed. Figs. 6, 7, 8 and 9 are details of the electrical terminal elements as hereinafter fully 30 described.

This invention is particularly related to sockets for electric signs or wherever the socket is seated behind a supporting plate or within a box or receptacle, and the invention comprises for the most part the electrical terminal members or parts located in the inner or closed end of the socket and from which the screw shell S is removable without removing the socket from the plate 35 or the respective terminals 2 and 3 from the socket. Not infrequently it occurs that the screw shell becomes injured or defective and requires replacement, and with my present construction the shell can be removed by merely loosening but not removing one of the terminals while the other one 40 remains fixed, and then a new screw shell can be substituted with ease and despatch and without disturbing the wiring within 45 the sign or box. By this improvement also the number of fastening screws is reduced and the usual mica insulating disk is eliminated and one of the fruitful sources of

leakage of the current is overcome. The present parts also are simplified in construction as compared with those hitherto used and are so disposed in relation to each other that short circuiting at any point is rendered impossible.

Now, returning to the construction of the parts it will be observed that the shell S has a central transverse opening a through its upper or outer portion about one-half the depth of the shell and approximately one-third the width, and that on either side 65 of this opening the remaining bottom portion consists of two flat side sections 4.

A feature of the socket B is a central post or projection 5 in the top thereof extending inward to such distance that it provides an 70 internal rest or seat for the head h of the terminal member 2 entirely removed from the other terminal member 3 and from the base of the shell. The said terminal 2 has a shouldered off-set g corresponding in depth 75 to the depth of post 5 so that the said terminal may rest its head h flat upon said 80 ing while the body thereof lies flat in the transverse channel c in the socket head, Fig. 5, and can be fixed therein by screw 6 at 85 one side of the center of the socket as shown in Fig. 4, the said terminal entering the 90 socket through one of the side recesses 7 therein. In this case the screw 6 is from without the socket though not necessarily, 95 and might be from within like screw 8 which secures the terminal 3. However, the screw 8 is necessarily engaged from within the socket because the invention is planned to use this screw as a means not only for fastening terminal 3 down upon the bottom sections of the shell but to release the same to allow the shell or thimble to be rotated a quarter turn to release it and withdraw it 100 bodily from the socket. To this end the screw remains always exposed where it can be reached by means of an ordinary screwdriver if small enough to enter the space at the side of the stud or post 5.

Now, respecting the said terminal member 100 3, it will be seen that said member as shown in Fig. 8 is of substantially T shape with a rounded recess 9 in its head between its arms b, which have relatively small lugs or studs d on their extremities and adapted to engage 105 in corresponding holes e in the bottom sec-

tions of the shell. Corresponding holes 10 are also formed in the head of the socket into which said lugs may penetrate more or less, and in operation the shell S is designed 5 to be inserted with its opening *a* directly over the cross arms *b*, and then pressed down so as to bring its bottom sections 4 flat on the inner surface of the socket. Meantime the terminal 3 is left free enough 10 on its fastening screw 8 to permit the said bottom flanges to be given a quarter turn beneath said arms and engage the studs *d* through the holes *e* therein. This being done the screw 8 is tightened and the shell 15 is thus locked against rotation while it is also brought into electrical connection with said terminal through said arms. The other terminal 2 is engaged upon its head *h* by the lamp, not shown, and the circuit through the 20 lamp is thus completed.

In Fig. 9 I show a modification of the terminal member 3, which also has the T shape with stem and arms adapted to be used in the same manner as the terminal in Fig. 8 25 but intended to be employed when post 5 in the socket is omitted. In such case the depression between the arms *b* serves to enlarge the space between said terminal and the terminal 2 and prevent possible short 30 circuiting.

It will be understood that the general practice is to seal the rear openings for screws 6 and 8 with wax or other insulating material, and therefore, the nut 12 for screw 35 8 retains its place when the screw is loosened or bodily removed to release and remove the screw shell. In this separation or assembling of the parts the right-handed relation of arms *b* to the body of terminal member 3 is important as is also the centrally alined position of the arms within the bottom of the socket.

What I claim is:

1. An electrical socket, a terminal therein 45 provided with two oppositely projecting arms having lugs on one side, a shell having bottom portions provided with holes adapt-

ed to be engaged by said lugs, and means to tighten said terminal on the socket and thereby fasten said shell. 50

2. In electric lamps, a socket and a shell therein having a transverse opening through the bottom thereof and flat bottom portions at the sides of said opening, in combination with a substantially T-shaped terminal engaging said bottom portions and a screw to fasten said terminal in the socket. 55

3. An electric socket and a partially divided shell therein having two flat bottom portions oppositely provided each with a 60 hole, in combination with a terminal having lateral arms with lugs on one side adapted to enter said holes and prevent rotation of said shell and a screw to lock said terminal in place. 65

4. An electric socket having a central post, a substantially T-shaped terminal having its arms extending laterally from the base of said post and a shell adapted to make electrical contact with said arms and 70 held in place thereby and a screw entered from the inside of said shell binding said terminal in place through said socket. 75

5. An electrical socket having a post centrally in its top, a terminal of substantially T-shape having a recess engaged about the base of said post and arms extending oppositely therefrom, a shell engaged beneath said arms and a screw fixing said terminal in place. 80

6. An electrical socket provided with a post at its middle and top extending inwardly, a substantially T-shaped terminal having arms extending oppositely from the base of said post, a shell having opposite 85 flat bottom portions engaged beneath said arms and interlocked therewith against rotation and a terminal resting on said post.

In testimony whereof I affix my signature in presence of two witnesses.

WILLIAM C. TREGONING.
